REGISTER INCORPORATING UNIDIRECTIONAL TRANSFER MEANS

This invention relates to a device to control a condition that is subject to adjustment by increments, which device comprises a bank of components adapted to vary the condition by increments of different magnitudes.

While the invention is widely adaptable for its basic purpose it has special utility as an instrument to control and/or measure an electrical value such as voltage, impedance, or frequency by means of a bank of components wherein the components provide increments of the value of different magnitudes to produce a closely controlled total value. Commonly, such an instrument is based on the decimal system and comprises a sequence of decade components each of which represents an order of 10 integers. For example, a widely used type of manually operated digital voltmeter comprises an array of four rotary components which, respectively control increments of 0.1, 0.01, 0.001 and 0.0001 volts from zero to 0.9999, the three higher order components employing rotary switches and the lowest order component incorporating either a rotary switch or a continuously variable electrical circuit element.

The important problem to which the invention is directed is to provide random access to any value in this wide range with rapid transverse over the whole range through transfer points where counts are carried over from one component to one or more higher order components. Such a capability for time saving operation is of economical importance because of the high hourly rate of specialized personnel and is mandatory if the instrument is to be employed to measure a value which may appear suddenly and briefly or to measure a value which drifts and varies widely.

An electronically controlled automatic digital voltmeter meets the requirement for rapid operation but such a voltmeter is not only an expensive instrument but is also highly complicated. The long standing pressing need is for a much less expensive and less complicated instrument capable of the same kind of random access and rapid traverse.

In one type of manual instrument heretofore available, a rapid jump or traverse between the two widely spaced values in the overall range is facilitated by employing a sequence of decade components which are individually manually operable but are mechanically independent of each other. The operator may make an extreme jump from a value of 0.1000 to a value of 0.9000 by simply manipulating the most significant decade component. The difficulty, however, is that a small shift through a transfer point may be a cumbersome and time-consuming operation. For example, a shift of an increment of 0.0001 through a multiple stage transfer point from 0.4999 to 0.5000 requires individual manipulation of all four components. Obviously the data produced by such an instrument will have a time gap at the transfer point and may omit entirely a significant change occurring during the hiatus.

A second type of manual instrument heretofore available solves the problem of rapid traverse through a multiple stage transfer point by interlocking the decade stages for automatic carry over from each lower order stage to a higher order stage. Such an instrument may incorporate a decade counting mechanism with a Geneva wheel to transfer a carry from one stage to a higher order stage. Since the stages are mechanically interlocked by the Geneva wheels, manual operation is necessarily restricted to the lowest order component. Only a slight turn of the lowest order component is necessary to shift through the multiple stage transfer point from 0.4999 to 0.5000. Unfortunately, however, a shift between widely separated values is slowed down to the rate of manual operation of the lowest order component. For example, with the instrument reading 0.5000 a traverse to 0.6000 would require cranking the lowest order component through 100 revolutions in a tedious and time-consuming manner.

An operator of the first type of manual instrument in following a changing value may make a rapid traverse between wide-

ly separated values but be defeated by a short traverse through a multiple stage transfer point and the operator of the second type of manual instrument may quickly follow a changing value through a multiple stage transfer point but be defeated by a sudden substantial increase or decrease in the changing value. The present invention combines the respective advantages of these two types of manual instruments with elimination of the disadvantages of both types.

Broadly described, the invention provides for interlocking individually manually operable decade components for automatic transfer to carry from one stage to a higher stage but employs a transmission means between stages that is unidirectional in that it locks a lower order stage against operation by the next higher order stage but freely transmits a carry from the lower order stage to the higher stage. Thus a selected component in the sequence may be individually operated with consequent operation of all higher stage components without affecting any lower stage component.

The unidirectional transmission means for transferring a carry from one stage to a higher order stage comprises a Geneva-type driver gear fixedly connected to the lower order stage, a driven gear carried by the higher order stage, and an intervening idler gear operatively connecting the Geneva drive gear with the driven gear, the idler gear normally functioning to lock the lower order Geneva drive gear against rotation by the higher order drive gear. Within the scope of the invention any suitable arrangement may be employed to make such a transfer mechanism unidirectional, i.e. to permit one stage along with higher stages to be manually operated independently of a locked lower stage.

One arrangement that may be employed incorporates detent means between the Geneva drive gear of the lower stage and the driven gear of the higher stage. For example, the idler gear may be spring-biased for disengagement either from the Geneva drive gear of the lower stage or from the driven gear of the higher stage in response to rise of the applied torque to a predetermined magnitude. Another practical arrangement incorporates detent means between the driven gear and the higher order stage on which it is mounted so that with the driven gear immobilized by the locked lower order stage, the higher order stage may be rotated independently of its driven gear. Both of these arrangements require the application of overriding force to the higher order stage, but a third arrangement that may be employed avoids this necessity by providing a clutch to disconnect a higher order stage of a pair of successive stages from the locked lower order stage of the pair, which clutch may be operated automatically if desired.

The invention further teaches that such an instrument may be constructed either as an in-line mechanism or as a coaxial mechanism. The in-line instrument has the rotary stages positioned side-by-side with corresponding manual knobs and corresponding number discs on the front side of the instrument. The coaxial instrument employs coaxial shafts with coaxial manual means and coaxial number discs on the front end of the instrument. In this regard a feature of the preferred practice of the invention is the provision of gear and detent components that may be used interchangeably in the fabrication of in-line and coaxial instruments. A further feature is the concept of combining the two types in a single instrument for special purposes.

The features and advantages of the invention may be further understood by reference to the following detailed description and the accompanying drawings.

In the drawings, which are to be regarded as merely illustrative:

FIG. 1 is a front elevation of a selected embodiment of the invention in a form of a manually operable voltmeter;

FIG. 2 is a plan view partly in section of a 4-stage counter that is employed in this embodiment;

FIG. 3 is a perspective view of the counter assembly with parts broken away;

FIG. 4 is a perspective view of an idler gear that is employed in the counter assembly;

FIG. 5 is a fragmentary diagrammatic sectional view showing how the idler is normally related with an associated Geneva type drive gear;

FIG. 6 is a fragmentary section along the line 6-6 of FIG. 2, showing how a detent pin is biased by a leaf spring;

FIG. 7 is an elevational view showing one face of a rotary switch that may be employed;

FIG. 8 is an elevational view showing the second face of the rotary switch;

FIG. 9 is a fragmentary plan view showing how an idler gear may be spring loaded to function as a detent means;

FIG. 10 is a fragmentary view partly in plan and partly in section showing a counter stage equipped with a clutch that is operable by very low torque applied manually to the counter;

FIG. 11 is a sectional view along the line 11-11 of FIG. 10 showing how a pair of microswitches is associated with the knob for operating the clutch;

FIG. 12 is an exploded view of the counterstage shown in FIG. 10;

FIG. 13 is a wiring diagram of the circuit employed in the manually operable voltmeter;

FIG. 14 is a wiring diagram of a circuit that may be employed for measuring impedance;

FIG. 15 is a plan view partly in section of a 4-stage coaxial counter assembly;

FIG. 16 is a front elevational view of the coaxial counter;

FIG. 17 is a diagrammatic plan view showing how a 4-stage in-line counter assembly may be combined with a coaxial counter assembly to provide an 8-stage counter;

FIG. 18 is a front elevation of the 8-stage counter as seen along the line 18-18 of FIG. 17;

FIG. 19 is a diagrammatic plan view showing how two coaxial 4-stage counter assemblies may be combined in tandem to provide an 8-stage counter;

FIG. 20 is a front elevational view of the counter in FIG. 19 as seen along the line 20-20;

FIG. 21 is a diagrammatic perspective view of a weighing apparatus incorporating the principles of the invention;

FIG. 22 is a diagrammatic plan view of structure shown in FIG. 21;

FIG. 23 is a longitudinal sectional view of a stack of interconnected weights that is used in the apparatus;

FIG. 24 is a diagrammatic perspective view showing how two of the weights of the stack are interconnected;

FIG. 25 is an elevational view of a cam that is used in the apparatus; and

FIG. 26 is a diagrammatic view of an embodiment of the invention for measuring hydraulic pressure.

FIGS. 1 to 8 show, by way of example, the structure that may be employed for a manually operable voltmeter incorporating the principles of the invention, the voltmeter having a range of 0.0001 to 0.9999 volts. Broadly described, this first embodiment of the invention comprises a counter assembly (FIG. 2) having four counters represented by four shafts 30A-30D. The four counters 30A-30D are equipped with corresponding manual knobs 32A-32D for actuating corresponding electrical components (FIG. 3) 34A-34D with the guidance of a null indicator 35 (FIG. 1). The four counters 30A-30D carry corresponding numbered discs 36A-36D and are shown in FIG. 1. The device may be mounted in a suitable housing 38 having four windows 40 for viewing the integers on the four discs.

The multiple stage counter may be based on any desired radix or system of measurement. In this instance the counter is based on the radix 10, each counter disc 36 having 10 stations bearing numerals 0-9 respectively.

The counter assembly may be mounted on a channel-shaped frame member having a bottom web 42 and two upright parallel flanges 44 in which the four shafts or counters 30A-30D are journaled.

The first three counters 30A, 30B and 30C fixedly carry corresponding Geneva-type drive gears 45A, 45B and 45C. The three counters 30B, 30C and 30D carry corresponding

driven gears 46B, 46C and 46D. It may be noted that for economy in the utilization of space the drive gears and the driven gears alternate in position. Thus the driven gear 46B is forward of the drive gear 45B on the counter 30B and the driven gear 46C is rearward of the drive gear 45C on the counter 30C.

Between the two counters of each pair of successive counters a suitable idler gear 48 operatively connects the drive gear of the lower counter of the pair to the driven gear of the higher counter of the pair. Thus an idler gear 48A permits the drive gear 45A of the first or lowest order counter 30A to actuate the driven gear 46B of the second counter 30B; an idler gear 48B permits the drive gear 45B of the second counter to actuate the driven gear 46C of the third counter 30C; and a third idler gear 48C permits the drive gear 45C of the third counter to actuate the driven gear 46D of the fourth counter 30D.

As best shown in FIG. 4 each of the idler gears has eight teeth 49 to actuate the corresponding driven gear and four alternate teeth of the eight teeth are extended in length to cooperate with the corresponding Geneva-type drive gear. As best shown in FIG. 3 each of the Geneva-type drive gears 45A-45C has a cylindrical peripheral portion 50 with a single transverse groove 52 to cooperate with the four extended teeth of the associated idler gear 48 and each of the Geneva-type drive gears is further formed with a pair of teeth 54 which extend the peripheral groove 52 and which cooperate with the eight teeth of the associated idler gear.

In a well known manner normally two of the four extended teeth 49 of an idler gear abut the peripheral portion 50 of the associated drive gear 45, as shown in FIG. 5, to lock the idler gear against rotation and thereby lock the associated driven gear 46 against rotation. Once in each revolution of a drive gear, the transverse groove 52 and the two teeth 54 of the drive gear engage the corresponding idler gear 48 to rotate the idler gear by two teeth and thus rotate the associated driven gear 46 by two teeth. Since each driven gear 46 has 20 teeth each rotation of the corresponding drive gear advances the driven gear by one-tenth of a revolution.

It is apparent that each set of gears comprising a drive gear 45, an idler gear 48 and a driven gear 46 serves as transfer means between the two counters of each pair of successive counters to transfer to the higher order counter of the pair a carry generated by the lower order counter. As heretofore pointed out, an important feature of the invention is that each of these transfer means is unidirectional to permit a carry to be transferred from the lower order counter of the pair to the higher order counter while preventing the higher order counter of the pair from operating the lower order counter. In other words each transfer means is releasable to permit manual rotation of the higher order counter independently of the lower order counter of each pair of successive counters.

In the first embodiment of the invention the unidirectional concept is carried out by providing detent means between the two counters of each pair of successive counters. As shown in FIG. 2 each counter or shaft 30 has an enlarged portion the periphery of which is formed with a circumferential series of 10 equally spaced longitudinal V-shaped grooves 55. Each of the drive gears 45 is fixedly mounted on the enlarged portion 60 of the corresponding counter by a diametrical pin 56 but each of the driven gears 46 is mounted on the corresponding counter 30 in a freely rotatable manner.

Each driven gear 46 has a relatively large hub portion 58 having two diametrically opposite radial bores in which two corresponding detent pins 60 are slidingly mounted and are spring biased into yielding engagement with the longitudinal grooves 55. In this particular embodiment of the invention each of the detent pins 60 is under the pressure of a corresponding leaf spring 62 that is flexed against the detent pin by a pair of lugs 64 on the driven gear. As indicated in FIG. 6 the two lugs 64 may be in the form of lateral extensions of two of the teeth of the driven gear. Each leaf spring 62 may be formed with a central dimple 65 (FIGS. 2 and 6) to seat the outer end of the corresponding detent pin, the dimple keeping the leaf spring centered relative to the detent pin.

By virtue of the yielding engagement of the detent pins 60 with the longitudinal grooves 55 of the corresponding counters 30, each driven gear 46 and the corresponding counter 30 normally rotate in unison, the driven gear rotating the counter whenever a carry is transferred to the driven gear from a lower order counter. If, however, any substantial torque is developed between a driven gear 46 and the counter 30 on which it is mounted, the detent pins 60 of the driven gear yield to permit relative rotation between the driven gear and the counter. If, for example, the driven gear 46B on the counter 30B is immobilized because the corresponding idler gear 48A is immobilized by the drive gear 45A, manual torque applied to the knob 32B will rotate the counter 30B with slippage between the counter and the driven gear 46B. Thus, overriding rotary force applied manually to the knob 32B causes operation of the counter 30B with possible carry to the higher counters 30C and 30D but without any effect on the lowest order counter 30A.

The described transfer means between the two counters of a pair of successive counters may be analyzed as comprising a self-locking gear train in combination with torque-limiting means which is a yielding detent connection. The gear train which comprises a Geneva-type drive gear 45 and an associated idler gear 48 is positively connected to the lower order counter and the torque-limiting yielding connection operatively connects the gear train to the higher order counter. The gear train is normally locked in the manner indicated in FIG. 5 but unlocks in response to an input or carry from the lower order counter. The torque limiter is capable of operating the higher order counter in response to a carry from the lower order counter but merely slips if the higher order counter is operated while the gear train is locked.

Thus the combination of the gear train and the torque-limiting means transmit inputs or carries from the lower order counter to the higher order counter but does not respond to inputs from the higher order counter.

For purposes of a voltmeter, the four electrical components 34A-34D which are controlled by the four counters 30A-30D respectively may be subdivisions of a circuit means shown diagrammatically in FIG. 13. In FIG. 13 the electrical component 34A operated by the lowest order counter 30A comprises a rotary potentiometer in which a contact 70 operated by the counter 30A traverses an 80 ohm resistor 72.

Component 34B comprises a series of 11 resistors 75 of 40 ohms each and a pair of spaced contacts 76 operated by the counter 30B. The two contacts 76 which move in unison straddle two of the 11 resistors 75 and are connected respectively to opposite ends of the resistor 72 of the first counter. Component 34C has a series of 11 200 ohm resistors 78 traversed by a pair of spaced contacts 80 that rotate with counter 30C and are connected to the opposite ends of the series of 11 resistors 75. In like manner component 34D has eleven 1,000 ohm resistors 82 in series traversed by a pair of spaced contacts 84 that are operated by counter 30D, the two contacts 55 being connected to the series of resistors 78.

The 11 resistors 82 are energized by a battery 85. One side of the previously mentioned null indicator 35 is connected to the contact 70 of the potentiometer 34A. A circuit 86 whose voltage is to be measured by the voltmeter is connected to the 60 other side of the null indicator.

As indicated in FIG. 3, each of the electrical components 34B, 34C and 34D may comprise two rotary switches 88 with the corresponding series of 11 resistors connected between the two switches. FIGS. 7 and 8 show the structure of a rotary switch 88, for example, the rotary switch which is associated with one of the two contacts 76 of the counter 34B.

The rotary switch 88 has a stator 90 fixedly mounted on the frame of the counter assembly and has a central rotor 92 that is keyed to the counter 34B for rotation therewith. The stator 90 has 10 fixed contacts 93 that are connected to the resistor 75 and the contact 76 extends radially from the rotor 92 to cooperate with the 10 contacts in sequence. A fixed contact 94 in wiping contact with rotor 92 is connected to one end of the resistor 72 of the potentiometer 34A.

In FIG. 13, is apparent that the two contacts 84 place two of the 1,000 ohm resistors 82 in parallel with a total resistance of 2,000 ohms, the combination having a resultant resistance of 1,000 ohms. With the battery 85 generating a constant 1 volt 5 each step by which the two contacts 84 are moved by one-tenth rotation of the counter 30D varies the voltage through the null indicator by 0.1000 volt. In like manner one-tenth rotation of the other three counters 30C, 30B and 30A vary the overall voltage by increments of 0.0100 volt, 0.0010 volt 10 and 0.0001 volt respectively. Thus in FIG. 1 the numerals in the windows 40 indicate an overall voltage value of 0.3310.

It is apparent that by virtue of the described unidirectional transfer means between successive counters, a higher order counter 15 may be manually operated independently of lower order counters. For example a quick shift of as much as 0.9000 volt may be made by simply rotating the knob 32D. On the other hand, one-tenth of a turn of the lowest order knob 32A can carry out a multiple stage transfer from the voltage 20 value of 0.4999 to the voltage value of 0.5000.

An important advantage of the invention is that combining a null indicator with the multiple stage mechanism makes it possible for the operator to follow various procedures for quickly matching an unknown voltage of an outside circuit 25 without the operator taking the trouble to make interim readings of the numbers on the disc 36A-36D. For example, assuming that an unknown voltage is 0.5001 and the adjustment of the instrument at the start is for the value 0.3579, a logical and timesaving trial and error procedure may be followed 30 that is set forth in the following sequential tabulation wherein the underlined digit in each number corresponds to the number disc reading of the knob that is being rotated and an asterisk indicates where a null point is passed and therefore manual rotation is to be shifted from one knob to the next 35 knob in sequence:

	DIAL READING 5179	RESULTING
40		NULL 5009
	<u>3</u> 579	low
	<u>4</u> 579	low
	<u>3</u> 579	high*
45	5479	high
	5379	high
	5279	high
	5179	high
	5079	high
	4979	high
	4879	low*
	4989	low
	4999	low
	5009	high*
	5008	high
50	5007	high
	5006	high
	5005	high
	5004	high
	5003	high
	5002	high
	5001	-null-

Another advantage of an embodiment of the invention that incorporates a detent means in each transfer means is that during a random access manipulation, i.e. during rotation of any knob above the lowest order, the detent action gives the operator a definite sensing of the number of digits that are added or subtracted by the rotation. In addition the detent means serves to center the rotary contact of each rotary switch at one of the associated 10 fixed contacts. A further advantage of the invention is the possibility of manually adjusting one stage independently of the next higher order stage as well as independently of the next lower order stage. To manipulate any given stage in this completely independent manner, it is necessary merely to grasp and immobilize the knob of the next higher order stage while the given stage is manipulated.

FIG. 9 indicates how another form of detent means may be incorporated in a transfer mechanism between two stages of the counter mechanism. In FIG. 9 an idler gear 100 has one set of four short 10-position 102 and a second set of four teeth 103, the two sets serving to engage a driven gear 104 and a Geneva type drive gear 106. The idler gear 100 is rotatably and slidably mounted on a shaft 108 and is normally held in its operative position by a coil spring 110 that encircles the shaft. Each of the four teeth 102 is tapered to provide two opposite cam surfaces 112. The drive gear 106 is, of course, fixedly mounted on the corresponding counter and the driven gear 104 is likewise fixedly mounted on its counter. To provide a 10-position detent action, the 20 teeth of the drive gear 104 are paired by webs or bridges 107 that interconnect ends of the teeth of each pair. Thus the tapered teeth 102 of the idler gear 100 "see" 10 large teeth instead of 20 small teeth. When the drive gear 106 of the lower order counter rotates into operating engagement with the idler gear 100 to transfer a carry to the higher order counter, the idler gear transmits the rotation to the driven gear 104 in the normal manner. If the higher order counter is individually manipulated, however, while the idler gear 100 is locked by the peripheral surface 50 of the drive gear 106 as shown in FIG. 5, the bridged teeth of the driven gear 104 act on the cam surfaces 112 of the four teeth 102 to cause the idler gear to retract out of engagement with the driven gear in opposition to the force exerted by the spring 10.

Here again the transfer mechanism shown in FIG. 9 comprises a self-locking gear train that is operatively connected to the lower order counter in combination with a torque-limiting means, the gear train being normally locked and unlocking in response to a carry from the lower order counter. In this instance, however, the torque-limiting means is incorporated in the gear train itself.

FIGS. 10, 11 and 12 show how clutch means instead of detent means may be incorporated in each transfer mechanism to permit a counter to be manipulated without affecting lower order counters. A shaft 114 which functions as a counter is journaled in the two upright flanges 44 of a counter assembly frame and fixedly carries a Geneva-type drive gear 115. The usual 20-tooth driven gear 116 is rotatably mounted on the shaft 114 and is held in abutment with the drive gear 115 by a spacer sleeve 118. The face of the driven gear 116 that abuts the drive gear 115 is formed with ten equally spaced recesses 120 to cooperate with the two longitudinal pins 122 of a clutch collar 124 that is slidably mounted on the shaft 114. The two longitudinal pins 122 of the clutch pin slidably extend through two corresponding bores 125 in the drive gear 115 and normally seat in a diametrical pair of the recesses 120. The clutch collar 124 is unitary with a tubular armature 126 of a cylindrical solenoid 128 that is mounted on a frame flange 44 by suitable fastening means 130.

The solenoid 128 is controlled by a pair of confronting microswitches 132 which are mounted on a collar 134 is fixedly mounted on the shaft 114. The collar 134 is spaced forward from the usual number disc 135 which is also fixedly mounted on the shaft. A knob 136 for manipulation of the shaft 114 is rotatably mounted on the shaft and is retained by suitable means such as a nut 138. The knob 136 has a radial ear 140 which extends between the two microswitches 132 and thus limits the relative rotation of the knob. The control circuit for the solenoid 128 includes wires 142 which extend through an axial bore in the shaft 114 and are connected to slip rings (not shown) inside the solenoid. The solenoid in turn is connected to a suitable EMF source by wires 144.

Normally the shaft 114 of the counter is rotated by means of the driven gear 116, the driven gear being periodically advanced by one-tenth of a rotation for a carry transferred from the next lower order counter. If, however, the operator grasps the knob 136 and rotates the knob in either direction, the ear 140 of the knob transmits the torque by pressure against one of the microswitches 132 with the consequence that the clutch sleeve 124 is immediately retracted to free the drive gear 115.

from the immobilized driven gear 116 and thus permit the knob to actuate the drive gear and the next higher order counter independently of the driven gear. The springs (not shown) in the two microswitches 132 are of adequate strength to overcome the inertia of the knob 136 to cause rotation of the knob in response to rotation of the shaft by a lower order idler gear without causing either microswitch to open. On the other hand, the springs of the microswitches are weak enough to respond to manipulation of the knob 136 with the required degree of sensitivity. Whenever the knob is released from manual manipulation the solenoid is deenergized to permit the spring 143 of the solenoid to return the clutch to its normal position, the spring acting on the tubular armature 126. The two pins 122 promptly seat in a pair of the recesses 120 to interlock the driven gear 116 with the drive gear 115.

FIG. 14 is a diagram of circuit means that may be employed with a counter assembly of the character described for the purpose of measuring an unknown impedance. The lowest order counter controls a contact 145 that traverses a circular potentiometer resistor 146. The upper end of the resistor 146 is connected to a rotary contact 148 of the second order counter, the contact being movable along a series of nine resistors 150. The upper end of the series of resistors 150 is connected to a rotary contact 152 of the third order counter which traverses a series of nine resistors 154. Finally the upper end of the series of resistors 154 is connected to a rotary contact 155 of the highest order counter, which contact traverses a series of nine resistors 156.

30 The positive side of a battery 158 is connected to the upper end of the series of resistors 156 and is also connected to a terminal 160. The negative side of the battery 158 is connected to a pair of parallel resistors R1 and R2 which are of equal value. Resistor R1 is connected to the contact 145 and to a null indicator 162. The second resistor R2 is also connected to the null indicator and is further connected to a second terminal 164. The outside impedance that is to be measured is connected across the two terminals 160 and 164.

It may be seen that the resistors 156, 154, 150 and 145 and the outside impedance form two adjacent legs of a Wheatstone bridge whereby the null indicator may be employed to ascertain when the total impedance of the subdivisions of the circuit means equals the unknown outside impedance. In a typical embodiment of the invention the value of the potentiometer resistor 146 is 10 ohms; each of the nine resistors 150 is a 10 ohm resistor; the nine resistors 154 are 100 ohm resistors; and the nine resistors 156 are 1,000 ohm resistors. This permits direct measurement of impedance as high as 10,000 ohms.

FIGS. 15 and 16 indicate the construction of a coaxially arranged mechanism for controlling the subdivisions of the circuit means shown in FIG. 14.

The coaxial instrument has a frame structure which comprises a series of different transverse plates interconnected by longitudinal rods 170 and spacer sleeves 172. The transverse plates comprise a front plate 174, two spaced rear plates 175 and 176 and three stators 90 of three previously described rotary switches 88. As shown in FIG. 16, the previously mentioned null indicator 162 may be mounted on the left edge of the front plate 174 and a bracket 186 may be mounted on the front plate to provide a rectangular window 186 for display of four digits. The four counters comprise four coaxial shafts 180A-180D, the inner and lowest order counter 180A having a manually operable knob 182 which is unitary with a number disc 184A. The coaxial shafts 180B, 180C and 180D have corresponding number discs 184B, 184C and 184D which are knurled to serve as manual means for individual control of the different counters.

70 The innermost and lowest order counter 180A is connected to a potentiometer 202 on the rear end of the instrument which incorporates the movable contact 145 and resistor 146 of FIG. 14. The lowest order counter 180A is formed with an enlargement on which is mounted a Geneva-type drive gear 204A of the character heretofore described and this drive gear

is operatively connected by an idler gear 205A to a driven gear 206B on an enlargement of the second order counter 180B. In the usual manner, the driven gear 206B incorporates detent means in the form of a pair of pins 208 which are biased by corresponding leaf springs 210 into yielding engagement with the longitudinal grooves 212 in the second order counter 180B.

It is to be noted that the drive gear 204A and the driven gear 206B are separated by the stator 90 of a rotary switch 88. For clarity of illustration all of the rotary switches 88 in FIG. 15 are simplified with omission of the various contacts of the rotary switches as well as omission of the resistors associated with the rotary switches. The rotary switch between the drive gear 204A and the driven gear 206B provides the rotary contact 148 of FIG. 14 that traverses the nine resistors 150.

The idler gear 205A is formed with a central circumferential groove 214 which seats in a notch of the adjacent stator 90 to restrain the idler gear against axial movement on a fixed shaft 115. The idler gear 205A has eight alternately short and long teeth 49 for cooperation with the drive gear 204A and has a separate series of eight short teeth 216 to actuate the driven gear 206B.

The enlargement of the second order counter 180B fixedly carries a corresponding drive gear 204B which is connected by an idler gear 205B with a driven gear 206C which is mounted by the usual detent means on an enlargement of the third order counter 180C. The idler gear 205B straddles the stator 90 of a rotary switch 88 which provides the previously mentioned rotary contact 152 of FIG. 14 for traversing the nine resistors 154. Finally, a Geneva-type drive gear 204C on the third order counter 180C is connected by an idler gear 205C with a driven gear 206D which is mounted by the usual detent means on an enlargement of the highest order counter 180D. The idler gear 205C straddles the stator 90 of a rotary switch 88 which provides the previously mentioned rotary contact 135 of FIG. 14 for traversing the nine resistors 156. The enlargement of the highest order counter 180D is provided with a radial pin 218 which cooperates with a fixed stop pin 220 to limit the rotation of the highest order counter to keep the counter from being rotated past the position corresponding to digit 9 on the number disc 184D.

It is apparent that the coaxial instrument shown in FIG. 15 incorporates the same principles as the in-line instrument shown in FIG. 2 and may be operated in the same manner with the same advantages. Being more compact in width dimension, the coaxial instrument may be used with special advantage in some installations where space is limited. It is contemplated that the gears of both the in-line instrument and the coaxial instrument will be made of plastic and will be of identical configurations for interchangeable use in the two types of instrument. It will be obvious to those skilled in the art that the coaxial instrument shown in FIG. 15 may incorporate the circuit means of FIG. 13 and, on the other hand, the in-line instrument of FIG. 2 may incorporate the circuit means of FIG. 14. It also may be appreciated that either of the two counter assemblies may be incorporated into an instrument that operates automatically instead of wholly manually.

FIG. 17 indicates diagrammatically how a four-stage in-line instrument 222 may be employed in tandem with a coaxial instrument 224 to provide a composite instrument displaying values in terms of eight integers. For this purpose the lowest order counter of the in-line instrument 222 is connected to the highest order counter of the coaxial instrument 224 by previously described unidirectional transfer means that is indicated by the dotted line 225. FIG. 18 shows how a bracket 226 extending across the front of the two instruments may provide two windows 228 to display the eight digits.

FIGS. 19 and 20 show how two coaxial instruments 230 and 232 may be used in tandem to display values in terms of eight digits, the combination making a composite instrument that is especially compact in width dimension. As indicated by dotted line 235 the lowest order counter of the coaxial instrument 230 is connected by previously described unidirectional

transfer mechanism with the highest order counter of the second coaxial instrument 232. As shown in FIG. 20, two brackets 236 mounted on the front ends of the two instruments respectively provide a pair of windows 238 to display the eight integers.

FIGS. 21-25 show the general construction of a weighting incorporating principles of the invention. The purpose of the apparatus is to use the type of counter mechanism heretofore described for the purpose of applying increments of weight to one pan of a balance to ascertain the weight of an object on the other pan of the balance. As shown in FIG. 21, the balance comprises an upright support structure 240 on which a rectangular beam 242 is free to rock, the beam having a pair of knife elements 244 resting in V-shaped seats 245. A first pan 246 is suspended from the beam 242 to receive an object 250 that is to be weighted. A second pan 252 receives increments of weight to make up a total weight for comparison with the unknown weight. The overhead beam 242 carries a null indicator in the form of a pointer 254 that traverses an arcuate scale 255.

The 260C, has a counter assembly in a casing 256 comprising a first or lowest order counter 260A, a second higher order counter 260B and a highest order counter 260C, the three counters being operated by manual knobs 262A 262C respectively and being equipped with three number discs 264A-264C respectively. The counter assembly may be based on any radix or system of measurement. In this particular embodiment of the invention, the device measures weights in terms of 30 ounces to the second decimal place and therefore each of the number discs has ten numerals which may be observed through three windows 265 respectively. The three counters 260A-260C are interconnected by previously described unidirectional transfer means (not shown) for transferring a carry from the lowest order counter to the second order counter and from the second order counter to the third order counter.

The lowest order counter 260A controls a corresponding cam 266A by means of a shaft 268A and the cam cooperates with a follower in the form of a roller 270A mounted on one face of a gear 272A. The gear 272A is on a rocker shaft 274A that carries an arm 275A for depositing weights on the pan 252. A stack 276A of nine weights is suspended from the outer end of the arm 275A by a cable 278A and the outer end of the arm is formed with a concentric surface 280 in tangential contact with the cable so that the cable may be raised and lowered along a vertical line without deviation from the vertical line.

As shown in FIG. 23 each weight 276 of a stack of weights has a central cavity 282, the cavity having a top wall 284 with an aperture 285 therein. Captive in each of the cavities with freedom for vertical movement therein is a disc 286 that is larger than the aperture 285. The disc 286 of the topmost weight 276 is connected to the cable 278. Each disc 286 in each cavity of the other eight weights is connected by a pin 288 to the next weight above. Preferably the weights 276 are shaped to nest together as indicated in FIG. 22, each weight having a circular recess 290 on its upper side and all of the weights except the bottom weight having a corresponding circular boss on its underside.

FIG. 23 shows the cable 278 slightly elevated to lift the topmost weight 276 free from the stack to leave eight of the weights supported by the pan 252. It is apparent that the series of weights 276 may be raised free from the pan 252 or may be lowered by steps to cause any number of the weights to rest on the pan. It may be understood by referring to FIG. 25 that clockwise rotation of the cam 266A through one revolution from the zero position lowers the stack of nine weights by steps to deposit the nine weights on the pan 252 in sequence, the last tenth of the revolution lifting the stack clear from the pan.

A feature of the invention is the concept of counterbalancing the stack of weights 276A to reduce the pressure of the follower 270A on the cam 266A. For this purpose a counterbalance gear 294A in mesh with the gear 272A controls a

counterweight arm 295A. The counterweight arm 295A carries a cable 296A to control a stack of nine counterweights 298A which are deposited on a fixed platform 300. Preferably the counterweights 298A weigh slightly less than the weights 276A for the purpose of biasing the roller 270A against the cam 266A. If desired, however, the counterweights 298A may be equal to the weights 276A, suitable spring means being used to bias the roller 270A against the cam.

The second order counter 260B operates a shaft 268B to control a cam 266B that functions in the previously described manner to operate a gear 272B to swing an arm 275B for controlling a stack of weights 276B and to operate a gear 294B to control corresponding counterweights 298C. The weights 276A, 276B and 276C respectively weigh 0.01 ounce 0.1 ounce and 1.0 ounce respectively.

It is apparent that the described mechanism may be operated in the same manner as the other embodiments of the invention to measure the weight of an unknown object. As previously described it is possible to measure the weight of the unknown object rapidly by manipulating the knobs in descending order while watching the pointer 254, there being no need to observe the numerals on number disc 264A—264C during such a procedure.

In summary, the invention as described to this point teaches, by way of example, how a precise magnitude of voltage, impedance or weight within a given range of magnitudes may be created by employing an increment-controlling multiple stage counter. The invention further teaches that an unknown magnitude of voltage, impedance or weight may be measured by balancing the unknown magnitude against a known magnitude created by means of a multiple stage counter. The fact that the invention may also be used to measure a force of unknown magnitude is apparent from FIG. 21 where a gravitational pull of unknown magnitude acting on the object 250 is, in effect, applied upwardly to the pan 252 and is opposed by the controlled increment of weight.

FIG. 26 shows diagrammatically, by way of example, how the same principles may be applied to measure force in the form of hydraulic pressure. In FIG. 26 the hydraulic pressure of unknown magnitude is confined in closed structure 310 which is in pressure communication through a tube 312 with one side of a pressure-responsive means in the form of a differential gage 314. The second side of the differential gage 314 is connected by a tube 315 to an upright hydraulic cylinder 316 the pressure in which is controlled by a piston 318. A piston rod 320 extends upward from the piston 318 and supports a platform 322. The previously described multiple stage counter mechanism shown in FIG. 21 may be employed to control the deposit of increments of weight 276A, 276B and 276C on the platform 322.

To obtain a precise measurement of the hydraulic pressure existing in the closed structure 310, increments of weight are added or withdrawn from the platform 322 until the differential gage 214 indicates that the opposing pressures are equal. It is apparent that the unknown pressure is applied to the differential gage 214 in one direction or respect and the pressure in the cylinder 316 created by the increments of weight is applied to the differential gage in the opposite direction or respect. In this particular instance the ratio that is employed at the comparison component 314 is 1:1 but it is obvious that the apparatus may be designed to employ any desired ratio between the two pressures. It is further obvious that the differential pressure gage may be replaced by a conventional U-tube manometer, a two-fluid differential manometer or a micromanometer.

Our description in specific detail of the selected embodiments of the invention will suggest various changes, substitutions and other departures from our disclosure within the spirit and scope of the appended claims. In the claims the term "electrical means" is to be understood as covering any combination of electrical or electronic elements either simple or complex including but not limited to inductance, mutual inductance, capacitance and resistance.

We claim:

1. In a device of the character described for changing a condition incrementally with wide choice in the size of the increments to be employed in making a change and with rapid traverse between widely separated magnitudes of the condition, the combination of:

a counter assembly comprising a plurality of rotary counters corresponding to successive orders of integers based on a given radix, each of said counters being individually adjustable only in two opposite rotary directions; a plurality of components corresponding to the plurality of counters, each component controlling increments of the condition corresponding in magnitude to the order of integers of the corresponding counter, each of the counters being operatively connected to the corresponding component with the overall numerical value indicated by the counter assembly having a given relation to the total of the increments for which the components are adjusted; a Geneva-type drive gear fixedly connected to each of at least all but the highest order counter for rotation therewith; a driven gear on the higher order counter of each of the pairs of successive counters; and an idler gear between the two counters of each pair of successive counters, the idler gear operatively connecting the Geneva-type gear of the lower order counter of the pair to the driven gear of the higher order counter of the pair, each idler gear together with the cooperating Geneva-type gear and driven gear constituting transfer means normally operatively connecting the lower order counter of the pair to the higher order counter of the pair for actuation thereof, said transfer means incorporating a yieldable detent connection between the drive gear of the lower order counter of the pair and the higher order counter of the pair to yield and thereby permit rotation of the higher order counter independently of the lower order counter.

2. A combination as set forth in claim 1 in which said yieldable detent connection is between the higher order counter and the driven gear on the higher order counter.

3. In a counter assembly, the combination of:

a plurality of rotary counters corresponding to successive orders of integers based on a given radix, each of said counters being individually adjustable; transfer means between the two counters of each pair of successive counters to transfer to the higher order counter of the pair a carry generated by the lower order counter,

means incorporated in each of said transfer means to prevent operation of the lower order counter of the pair by the higher order counter of the pair; and

clutch means included in each of said transfer means, the clutch means being manually releasable to permit the higher order counter of the pair to be operated independently of the lower order counter, said clutch means being normally engaged and being releasable in response solely to manual rotation of the higher order counter.

4. In a counter assembly, the combination of:

a plurality of rotary counters corresponding to the successive orders of integers based on a given radix;

a corresponding plurality of knobs for manual operation to adjust the rotary counters respectively,

each of said knobs being restricted to a given axial position for adjustment rotation at the given axial position;

transfer means between the two counters of each pair of successive counters to transfer to the higher order counter of the pair a carry generated by the lower order counter of the pair,

the higher order counter of each such pair being operatively responsive to the lower order counter of the pair through the corresponding transfer means,

the lower order counter of each such pair being nonresponsive to manual rotation of the knob of the higher order counter at said given axial position of the knob,

whereby manual rotation of the knob of the higher order counter of the pair operates the corresponding higher order counter and may operate counters above the higher order counter without operating any counter of a lower order than said higher order counter.

5. In a device of the character described for changing a condition incrementally with wide choice in the size of the increments to be employed in making a change and with rapid traverse between widely separated magnitudes of the condition, the combination of:

- a counter assembly comprising: a plurality of rotary counters corresponding to successive orders of integers based on a given radix;
- a corresponding plurality of knobs for manual operation to adjust the rotary counters respectively, each of said knobs having a given axial position for rotation at the given axial position;
- a plurality of components corresponding to the plurality of counters, each component controlling increments of the condition corresponding in magnitude to the order of integers of the corresponding counter, each of the counters being operatively connected to the corresponding component with the overall numerical value indicated by the counter assembly having a given relation to the total of the increments for which the components are adjusted; and
- transfer means between the two counters of each pair of successive counters to transfer to the higher order counter of the pair a carry generated by lower order counter, the higher order counter of each such pair being operatively responsive to the lower order counter of the pair through the corresponding transfer means, the lower order counter of each such pair being nonresponsive to manual rotation of the knob of the higher order counter at said given axial position of the knob, whereby manual rotation of the knob of the higher order counter of the pair operates the corresponding higher order counter and may operate counters above the higher order counter without operating any counter of a lower order than said higher order counter.

6. In a device of the character described for changing a condition incrementally with wide choice in the size of the increments to be employed in making a change and with rapid traverse between widely separated magnitudes of the condition, the combination of:

- a counter assembly comprising: a plurality of manually operable rotary counters corresponding to successive orders of integers based on a given radix, each of said counters being individually adjustable only in two opposite rotary directions;
- a plurality of components corresponding to the plurality of counters, each component controlling increments of the condition corresponding in magnitude to the order of integers of the corresponding counter, each of the counters being operatively connected to the corresponding component with the overall numerical value indicated by the counter assembly having a given relation to the total of the increments for which the components are adjusted; and
- transfer means between the two counters of each pair of successive counters to transfer to the higher order counter of the pair a carry generated by the lower order counter, each of said transfer means being responsive to the rotation of the lower order counter of the pair to transmit a carry from the lower order counter of the pair to the higher order counter, but being nonresponsive to manual rotation of the higher order counter.

7. A combination as set forth in claim 6 in which each of

said transfer means includes a self-locking gear train and torque-limiting means,

the gear train being normally locked and being responsive to the lower order counter to unlock in response to input from the lower order counter, said torque-limiting means yielding to permit operation of the higher order counter independently of the lower order counter.

8. A combination as set forth in claim 7 in which said gear train includes a Geneva-type drive gear connected to the lower order counter for rotation therewith and an idler gear actuated by the Geneva-type gear to transmit a carry from the lower order counter, the idler gear being normally locked by the periphery of the Geneva-type gear.

15. 9. A combination as set forth in claim 7 in which the torque-limiting means is incorporated in the gear train.

10. A combination as set forth in claim 6 in which each of said transfer means comprises a self-locking gear train positively connected to the lower order counter and a torque-limiting yielding connection between the gear train and the higher order counter,

said gear train being normally locked and being responsive to the lower order counter to unlock in response to input from the lower order counter, said torque-limiting yielding connection being responsive to the lower order counter to unlock in response to input from the lower order counter, said torque-limiting yielding connection being effective to transmit carries from the gear train to the higher order counter and yielding when the higher order counter is operated while the gear train is locked.

11. In a device of the character described for changing a condition incrementally with the wide choice in the size of the increments to be employed in making a change and with rapid traverse between widely separated magnitudes of the condition, the combination of:

a counter assembly comprising a plurality of rotary counters corresponding to successive orders of integers based on a given radix, each of said counters being individually adjustable;

a plurality of components corresponding to the plurality of counters, each component controlling increments of the condition corresponding in magnitude to the order of integers of the corresponding counter,

each of the counters being operatively connected to the corresponding component with the overall numerical value indicated by the counter assembly having a given relation to the total of the increments for which the components are adjusted;

transfer means between the two counters of each pair of successive counters to transfer to the higher order counter of the pair a carry generated by the lower order counter,

means incorporated in each of said transfer means to prevent operation of the lower order counter of the pair by the higher order counter of the pair; and

clutch means included in each of said transfer means, the clutch means being manually releasable to permit the higher order counter of the pair to be operated independently of the lower order counter, said clutch means being normally engaged and being releasable in response solely to manual rotation of the higher order counter.

12. A combination as set forth in claim 11 which includes manual means for manual manipulation of each counter; and in which each of said transfer means includes electromagnetic means to release the corresponding clutch means, said electromagnetic means being responsive to application of torque force to the higher order counter means by the corresponding manual means.
